UNITED STATES PATENT OFFICE.

ABRAM A. RHEUTAN, OF WORCESTER, MASSACHUSETTS.

ENVELOP-CUTTING MECHANISM.

No. 853,597.

Specification of Letters Patent.

Patented May 14, 1907.

Application filed February 9, 1907. Serial No. 356,590.

To all whom it may concern:

Be it known that I, ABRAM A. RHEUTAN, a citizen of the United States, residing at Worcester, in the county of Worcester and State of Massachusetts, have invented a new and useful Envelop-Cutting Mechanism, of which the following is a specification, reference being made therein to the accompanying drawings.

10 The prime object of my present invention is to provide a convenient and efficient means for accurately cutting out the internal angle forms on envelop blanks; said means having facilities for rectangular enlargement and reduction whereby it is adjustable for many different sizes and for envelop blanks of various shapes and styles.

Another object is to provide an envelop cutting mechanism of the character described, 20 with an attachable and detachable supplemental extension appliance for use in cutting blanks having an extra long flap, or for "side-seamed" envelopes and the like.

Another object is to provide an envelop 25 cutting die or means for cutting out the internal angle forms of envelop blanks, with a detachable interset cutting appliance for cutting an opening or slit in the area of the blanks; as for "outlook" envelopes, or similar 30 purposes.

I attain these objects by the mechanism illustrated in the accompanying drawings, wherein

Figure 1 represents a top plan view of the 35 mechanism embodying my invention. Fig. 2 is an elevation view of the same. Fig. 3 is a sectional view at line XX showing the interset cutting appliances, and Fig. 4 represents a transverse section of a device for locking together the edges of the main and extension blades.

It will be understood that this improved mechanism is adapted as a cutting-die to be employed in a cutter-press having a flat plate 45 follower, such as are commonly used when cutting paper and other material with dies. The cutting-blades are made of uniform height with straight or level top and bottom edges to match the plate of the cutter-press.

50 My improved mechanism, as shown in the drawings, comprises the four corner sections or blocks indicated by reference numerals 1, 2, 3, 4, each carrying a cutter-blade of suitable angular shape on plan, said blades each 55 having its top edge approximately square and flush with the top surface of the section

block, and its lower edge properly ground to a cutting edge. The cutter blades, respectively indicated at C¹, C², C³ and C⁴, are formed with an angle contour 5 of the desired 60 shape for the internal angle forms to be cut from the envelop blanks, and with wing portions 6 and 7 that extend in either direction approximately as shown. The wing portions 7 are shown in parallel planes, and the 65 portions 6 in planes inclined to each other; but these forms may be modified in some instances for peculiar styles of blanks. The dotted line e indicates the fold line representing the face area of an envelop for which the 70 cutters are at present adjusted.

In practice the blades are about three and one half inches in depth, and the corner blocks about one inch, more or less. The 75 blades are secured to the blocks by screws, as indicated by dotted lines on Fig. 1. The four corner sections are connected by rods in a manner for adjustment thereon. Each corner section is provided with a guide rod having its end rigidly fixed therein, and extending horizontally and in rectangular order, 80 with a slidable fit through an opening in the opposite or next adjacent corner section. These rods are indicated at D¹, D², D³ and D⁴. The end of the rod can be secured by a 85 nut, as at 8, or can be threaded into the metal of the block, as at 9; or it may be otherwise fixed therein. Each corner section is provided with a set-screw or means for firmly clamping the guide rod that passes 90 through it, as indicated at F¹, F², F³ and F⁴. The outer sides of the rods are best slabbed off flat to give a square seating face for the end of the set-screw. The guide rods can be of any convenient length desired. By loosening the clamping means F² and F⁴ of the corner sections 2 and 4, the transverse dimension 95 between the cutter-blades can be increased or reduced; and by loosening the clamping means F¹ and F³ of the corner sections 1 and 3, the longitudinal dimension between the cutter-blades can be enlarged or reduced. Thus the die or cutting means may be adjusted for any size or proportional 100 form of rectangular envelop shapes. At all 105 positions of adjustment the parts maintain their rectangular relation, and the adjustment is effected without changing the relative angularity of the cutting blades in respect to the longitudinal and transverse axes 110 of the die.

For instances wherein the envelop blanks

are to have an extra long flap, I provide the mechanism with a supplemental extension appliance, which consists of two carriers or brackets 12 and 13, each having an extension blade 17 attached thereto, the end of which is adapted to abut against the end of the regular cutter-blade at 15. One of said carrier-blocks 12 is fitted to slide onto and be clamped by the screw 14 to one of the guide-
5 rods, as D⁴, and is provided with a transversely projecting rod 16 fixed therein, and upon which the other supplemental-blade carrier 13 is adjustably secured by a suitable clamp device and screws 19. This construction permits adjustment of the cutter extension members to co-operate with the lateral enlargement or reduction of the main portion of the mechanism. The extension can be used at either end of the die. The carrier-
10 members 12 and 13 are preferably made to lap onto the main cutter-blade and have one or more bolts 18 that screw thereinto, as indicated. At the adjacent ends 15 of the blades I provide means for locking them together to
15 prevent their springing out of alinement. It consists of a disk 20 having an inwardly offset peripheral flange 21 and a central threaded stud 23. A threaded opening is formed at the joint, half in each blade, (see Figs. 2 and 4) and a circular grooved recess 25 is formed in the blades to correspond with and receive the disk. When screwed into place the thread holds the two blade sections in line, and the groove 25 and flange 21 prevents their spreading apart endwise. The mechanism can be employed with or without this supplemental extension appliance according to the requirements of the work to be performed.

40 For some classes of envelops it is desired to cut an opening or slit, of some form, within the area of the blank. For such purpose I provide a detachable interset cutter 30 having an arm or supporter 32 that is adjustably securable to any one of the guide-rods that connect the corner sections. In the present instance I show the interset cutter 30 formed for cutting what are known as "outlook" openings in the blanks. Said cutter is attached to the slotted arm 32 by bolts 33, and said arm is clamped to the rod D⁴ by the binding screws 34, or other efficient means. The cutter 30 can be made of any required form for cutting a hole or slit, one or more as required, and its supporting arm 32 can be made for giving the cutter such position as may in any instance be desired. It may also be used in connection with either of the guide rods. The interset cutter can be omitted in instances where no openings or slits are to occur in the blanks.

What I claim as my invention and desire to secure by Letters Patent, is

1. A mechanism of the character specified, comprising a series of four cutter-supporting

corner blocks having blade-seating faces in approximate conformity to the respective angle planes, a series of horizontally disposed guide-rods arranged in rectangular order extending through and adjustably connecting adjacent blocks, an angle-cutting blade attached to the seating faces on each of said corner blocks, and means for securing the respective corner-blocks and guide-rods at positions of adjustment in relation to each other.

2. An adjustable die for the purpose specified, comprising four corner sections with angle cutting blades, each section having a rod rigidly fixed therein and extending adjustably through the opposite section in rectangular series, and means at each section for clamping the rod that is adjustable therein.

3. An adjustable die for cutting the internal angles in envelop blanks, comprising a series of corner blocks having openings formed at right angle therein, angle-cutting blades secured to said corner blocks and longitudinal and transversely disposed rods arranged in said openings to permit adjustment of the blocks and cutters toward and from each other while maintaining rectangular relation of the rods and without changing the relative angularity of the several cutting blades in respect to the longitudinal and transverse axes of the die.

4. The combination, of the four corner section-blocks, angle-cutting blades respectively attached to and extending beyond said section-blocks, section-connecting rods disposed in rectangular form, said rods severally secured at one end to the section block and cutter and extending through an opening in the next section block and cutter with a sliding fit, and a set-screw or clamping means for securing the rod, in each section-block, substantially as set forth.

5. In an envelop cutting die of the character described, the combination with the expandible and contractible main die, comprising the corner-section blades and rectangularly disposed connecting rods; of the detachable supplementary extension appliance comprising blade-extension members, a carrier for one of said members adjustably mountable on one of said connecting rods and having a transverse rod fixed therein, a carrier for the other blade-extension member mounted adjustable on said transverse rod, and means for securing the parts at adjusted positions.

6. The combination in an envelop-cutting die mechanism, of four corner-section blocks having corner cutters for cutting out internal angles on envelop blanks, four corner-connecting rods disposed in rectangular form extending through and supporting said corner-section blocks in the same plane, an interset cutter comprising a cutting member for forming an opening or slit in the area of the

blank, and a carrier arm on which said cutting-member is secured; said arm provided with an attaching portion that embraces the corner-connecting rod, and means for its adjustable affixment on said rod.

7. In a mechanism of the class described, the combination, with a main adjustable corner-cutting die having the corner-cutting sections and section-connecting rods; of an interset cutter provided with a carrier arm adapted for attachment to one of the section-connecting rods, for the purpose set forth.

8. In a mechanism of the character described, the combination with the abutting ends of the main cutter-blade, and a cutter-

blade employed as an extension thereof, each having a half circular grooved recess in its face; of an edge-locking device comprising an inwardly flanged disk having a screw-threaded stud at the center thereof, said device threaded into an opening at the junction of the blades with the flanged disk fitting a corresponding recess in the face of the blades, substantially as set forth. 20

Witness my hand this 6th day of February, 25
1907.
